[57] CLAIM

The ornamental design for a top mount fan fold paper collector, as shown and described.

DESCRIPTION

FIG. 1 is a top, front and right side perspective view of a top mount fan fold paper collector showing my new design;

FIG. 2 is a left side elevational view thereof, the right side being a mirror image of the left side shown;

FIG. 3 is a front elevational view thereof;

FIG. 4 is a rear elevational view thereof;

FIG. 5 is a top plan view thereof; and

FIG. 6 is a bottom plan view thereof.
